UNITED STATES PATENT OFFICE.

MAXWELL W. KIMMERLING, OF WASHINGTON, DISTRICT OF COLUMBIA.

ENGINE PISTON.

Application filed October 23, 1924. Serial No. 745,349.

To all whom it may concern:

Be it known that I, MAXWELL W. KIMMERLING, a citizen of the United States, residing at Washington, in the District of Columbia, have invented certain new and useful Improvements in Engine Pistons, of which the following is a specification.

This invention relates to an engine piston, and particularly to a construction embodying a yielding piston head adapted for use in an explosive type of engine to effect the complete evacuation of burnt gases upon the exhaust stroke and also to provide a supplemental compression upon the stroke of the piston for compression.

In this construction of piston it is important to provide means whereby the piston head may be readily removed when necessary without the disconnection of the piston rods therefrom or from the engine crank shaft, and the removal of this head permits the replacement when necessary of either the tension spring or piston rings. Further, in prior constructions on the exhaust stroke of the piston the yielding of the head results in an untraveled area or space at the end of the cylinder which prevents thorough scavenging of the burnt gases therefrom and from the cylinder head, and to obviate such objections means are provided on the head to compensate for such space and also to enter the head space for the ejection of gases therefrom.

Under the compression stroke the spring tension of the head supplements the piston pressure to secure more even and effective compression while in the firing stroke this tension acts upon the expanding fuel to maintain a constant pressure thereof for substantially the full stroke. Under normal conditions the gas expansion reduces the pressure as the piston head moves outward and the reaction of the spring against the fuel equalizes the pressure within the cylinder to secure the most even and smooth driving effect upon the engine.

The invention has for an object to provide a novel and improved construction of engine piston comprising a body having a piston rod connected thereto and a piston head slidably mounted thereon with tension means for projecting said head and securing means accessible at the exposed face of the head for connecting the same to the body.

Another object of the invention is to provide an improved construction of piston

head having a curved or spherical pressure face and longitudinally movable upon the piston rod to enter or travel into the fuel space of the engine head at the exhaust stroke of the piston.

A further object of the invention is to provide an improved construction of piston comprising a body and a cooperating head normally projected therefrom by an interposed spring, together with a yoke slidably mounted upon the wrist pin of the piston rod and detachably connected to the head by fastening means extending therethrough and accessible without disconnection of the piston rod.

Other and further objects and advantages of the invention will be hereinafter set forth and the novel features thereof defined by the appended claims.

In the drawings:—

Figure 1 is a vertical section showing the application of the invention at the end of the exhaust stroke;

Figure 2 is a similar view showing the parts in position for the compression stroke at the time of firing;

Figure 3 is a central vertical section through the piston;

Figure 4 is a similar view at a right angle to Figure 3;

Figure 5 is a top plan of the piston;

Figure 6 is a bottom plan thereof;

Figure 7 is a section on the line 7—7 of Figure 4; and

Figure 8 is a detail perspective of the connecting yoke.

Like numerals refer to like parts throughout the several figures of the drawing.

The invention is adapted for application to any desired type of internal combustion engine and the size and general configuration of the piston may be adapted for the particular type of engine to which it is to be applied.

In the form shown the engine 10 is provided with the usual cylinder 11 and the engine head 12 provided with the fuel or combustion chamber 13 into which a spark plug 14 extends. This chamber has the usual valve connections for intake and exhaust, the latter being shown at 15 and communicating with an exhaust passage 16. Within the cylinder the piston 17 is disposed and this member may be formed of any desired material, preferably of an aluminum alloy, and is connected by the rod 18 with

the crank shaft in the ordinary manner. The piston comprises two members movable relatively to each other and a preferred form constitutes the body or sleeve 20 which is formed with inwardly extending bearings 21 to receive the wrist pin 22 which is clamped upon the rod 18 in the usual manner, as shown at 23.

The piston or head 17 is slidably mounted 10 on the body and comprises an extended or spherical pressure face 24 and a skirt portion 25 which is provided with a series of apertures 26 effecting a cooling action as well as permitting the introduction of oil to the 15 contacting surfaces between the skirt and the body 20. This piston head is also provided with the usual piston rings 27 while disposed between the inner face of the head and the body 20 is a tension spring 28 of 20 suitable strength to normally project the piston head away from the body and maintain such projection to a certain extent even under conditions of compression.

In order to prevent friction in the movement of this spring and also overheating thereof, the body 20 is formed at its upper portion with openings 29 which communicate with the space between the body and head.

30 For the purpose of connecting the head to the connecting rod and body so as to permit the convenient removal of the head whenever desired without disconnection of the rod, a yoke member 30 is connected to 35 the head by means of a fastening device such as a bolt 31 extending through the exposed pressure face 24 of the head and threaded into the aperture 32 of the yoke. This yoke is seated in an angular recess 38 of the head 40 to prevent rotative movement. In order to provide a smooth finish this bolt head may be seated in a suitable recess 33 and for the further purpose of securing the same against unthreading, recesses 34 are provided at opposite sides of the bolt and adapted to receive a cotter pin or other securing device as shown at 35 which passes through properly aligned apertures in the head and bolt. The extended walls 36 of the yoke are each 50 provided with an elongated aperture 37 which embraces the wrist pin 22 and permits a sliding movement of the yoke thereon. These walls 36 are preferably disposed intermediate of the bearings 21 and the rod connection with the wrist pin and are thus guided in their vertical movement while the extent of travel of the head in its expansive and retractive movements is limited by the end walls of the elongated slots 37.

60 In the operation of the invention, with the parts in the position shown in Figure 1, the head of the piston extends into the fuel chamber of the engine head and thus more efficiently expels therefrom all burnt gases 65 when the exhaust valve is opened, the piston

head being at this time in its normal condition when not subjected to pressure. Upon the closing of the exhaust valve and the opening of the intake valve the outward movement of the piston produces a suction 70 intake of fuel which is materially increased owing to the spherical configuration of the head which has displaced the fluid contents of the chamber in the engine head and as a result draws in a greater charge with a more effective suction action. 75

Upon the further stroke of the piston for compression purposes it travels to the position shown in Figure 2, at which time the compressed body of fuel acts upon the head causing the same to retract and place the spring under tension, this tension maintaining a greater pressure or compression in the fuel body. Under these conditions the compression of the piston head leaves a space or area at the end of the cylinder and the spherical head compensates for this space as it is adapted to travel more or less into the fuel chamber of the engine head. 80

When the parts in Figure 2 are in position 90 for firing and upon the firing stroke, the compression of the piston head is maintained until the expansion of the fuel causes the compression thereof to be reduced in the travel of the piston and during this travel 95 the head is projected from the piston body under the spring tension to maintain a practically equal pressure of the exploded gas during the entire travel of the piston.

From the construction shown it will be 100 seen that this type of piston permits the removal of a head for replacement or repair of either the spring or rings without disturbing the rod connections and thus greatly reduces the time required for that purpose and permits access to the piston parts by the simple removal of the engine head as ordinarily for cleaning purposes. Furthermore, the cylindrical construction of this head presents a curved face adapted to travel into the chamber of the engine head and thus most effectually produce the scavenging action upon exhaust. The mounting of the head upon the wrist pin by means of the yoke provides an additional guiding function while limiting the extent of the expansive and contractive movements of the spring relative to the body of the piston. 110

115 It will be seen that the invention presents a very simple, efficient and economical device adapted to produce the most efficient results in a piston for internal combustion.

120 While the details of construction have been specifically shown and described, still the invention is not confined thereto as changes and alterations may be made therein without departing from the spirit of the invention as defined by the appended claims.

125 Having thus described my invention, what 130

I claim as new and desire to secure by Letters Patent is:

1. In an engine piston, a body, a piston rod having a wrist pin pivoted upon the body, a piston head slidably mounted upon the body, tension means for projecting said head, means extending inward from the pressure face of the head and slidably connected with the body, and securing means for connecting said head to the slidable means accessible at the outer surface of said pressure face. 70
2. In an engine piston, a body, a piston rod having a wrist pin connected thereto, a piston rod slidably mounted upon the body tension means for projecting said head, depending means carried by said head for limiting its movement upon said body by engagement with said wrist pin, and securing means for connecting said depending means to the head accessible at the pressure face thereof. 80
3. In an engine piston, a body, a piston rod connected thereto and provided with a wrist pin, a piston head slidably mounted upon the body, tension means for projecting said head, securing means for connecting said head to the body accessible at the pressure face of the head, and a member secured 85 to the head and embracing the wrist pin of the connecting rod to limit the relative movement of the head upon the body. 90
4. In an engine piston, a body, a piston rod connected thereto, a piston head slidably mounted upon the body, tension means for projecting said head, a support connected to said head and slidably mounted upon the body, and a securing device for said support. 100
5. In an engine, a cylinder and cooperating engine head, a piston comprising a body, a piston rod having a wrist pin mounted thereon, a piston head yieldingly carried by said body and provided with a spherical pressure face disposed to enter and substantially fill the head space beyond the cylinder, and securing means extending inward from said face for detachably mounting the head upon said wrist pin. 105
6. In an engine piston, a body, a piston rod having a wrist pin mounted in the body, a head provided with a curved pressure face, a perforated skirt carried by said head to completely enclose said body, a tension spring disposed between said body and the inner face of the head, and securing means extending between said face and the wrist pin and having means at the outer face of the head for removably connecting the head to said securing means. 110
7. An engine piston comprising a body having a wrist pin mounting, a piston head movable relative to the body, tension means disposed between the body and head to project the latter, means within the head for 115
- limiting its movement relative to the wrist pin, and a securing device for said limiting means accessible at the outer face of the head. 120
8. In an engine piston, a body, a piston rod mounted therein, a head enclosing said body and provided with a spherical pressure face, a tension spring disposed between said body and the inner face of said head, and a securing bolt extending through said spherical face for connecting the head to said body. 125
9. In an engine piston, a body, a piston rod mounted therein, a head enclosing said body and provided with a spherical pressure face, a tension spring disposed between said body and the inner face of said head, a yoke connecting said head and body and provided with elongated slots to permit relative movement of the parts, and a bolt extending through said spherical face and threaded into said yoke. 130
10. In an engine piston, a body provided with wrist pin bearings, a piston head embracing the same, tension means disposed between said body and head, a connecting member mounted upon the inner face of the head to limit its travel relative to said bearings, and means for detachably mounting said member upon the head. 135
11. In an engine piston, a piston head, a connecting member mounted upon the inner face of the head, an attaching device for said member having operating means accessible at the outer surface of said face, and locking means mounted in said surface and extending through said operating means. 140
12. In an engine piston, a body, a connecting rod having a wrist pin pivoted in bearings at opposite sides of said body, a head having a skirt embracing said body, a connection from said head comprising parallel slotted flanges disposed between the connecting rod and said bearing, and an attaching device extending through the head to said connection. 145
13. In an engine piston, a body having a solid cylindrical wall and provided at opposite sides with bearings and intermediate openings through the body, a head provided with a perforated skirt contacting with said wall, a connecting rod mounted in said bearings, and means for detachably connecting the head to said body. 150
14. In an engine piston, a body, a connecting rod provided with a wrist pin pivotally mounted therein, a cylindrical head enclosing said body, a tension spring disposed within said head to normally support the same from said body, a yoke seated in said head against rotation and provided with slotted flanges embracing said wrist pin, and a securing bolt extending through the pressure face of said head and threaded into said yoke. 155

15. In an engine piston, a body, a connecting rod provided with a wrist pin pivotally mounted therein, a cylindrical head enclosing said body, a tension spring disposed within said head to normally support the same from said body, a yoke seated in said head against rotation and provided with slotted flanges embracing said wrist pin, a curved

pressure face upon said head provided with a central recess, an attaching bolt threaded 10 into said yoke and having its head seated in said recess, and a locking device insertable through said recess to retain the bolt head against rotation.

In testimony whereof I affix my signature.
MAXWELL W. KIMMERLING.
